trustee

Application August 2, 1940, Serial No. 349,531

6 Claims. (Cl. 242—6)

This invention relates to machines for wrapping with strip material open-centered articles, such as coils of wire, rolls of metal strip, vehicle tires and other objects of toric form, which for convenience I shall herein refer to as coils, and more particularly to mechanism for controlling the paying out of the wrapping strip during the wrapping operation. The invention provides an improved arrangement permitting a given machine to handle a greater range of sizes than is now possible and permitting a rapid adjustment for sizes. The invention also contemplates the provision of a mechanism which will make possible the use of strip material packaged in rolls without any central core and provides for easy changing of such rolls.

The invention will be well understood by reference to the following description of an illustrative embodiment thereof shown by way of example in the accompanying drawings, wherein:

Fig. 1 is an end elevation of a wrapping machine exemplifying the invention, various parts being omitted for clearness and parts broken away;

Fig. 2 is an elevation on an enlarged scale of 25 the strip dispensing mechanism proper; and

Fig. 3 is a fragmentary detail view of a portion thereof as seen from the left of Fig. 2.

In Fig. 1 I have shown a wrapping machine of known type comprising a revolving shuttle or wrapping head 6 in the form of an incomplete annulus suspended exteriorly by the rolls 8 and herein frictionally driven from two of these rolls, those at the right hand in Fig. 1, which are themselves driven by a friction disc 10 taking motion from an electric motor 12 on the base 14 of the machine. The coil C may be supported on a pair of rolls 16, one of which appears in Fig. 1, and is held upright thereon by suitable devices of which I have illustrated lateral supporting rolls 18 which, however, are shown broken away in order not to obscure other elements. The machine illustrated is of the type wherein the coil is wrapped at the top and the rolls 16 and cooperating mechanism support the coil with its upper portion interlinked with the shuttle, the coil being inserted through gap 28 in the shuttle. The end of the wrapping strip S carried by the shuttle is applied to the coil, and when the latter is revolved by the supporting rolls 16, which are driven in the usual manner by means not necessary to illustrate or describe in detail, and at the same time the shuttle is revolved the strip is drawn off from the latter and wrapped helically about the coil. The strip S is here illustrated 55

as of heavy craped paper, a material commonly used.

The tension on the strip during the operation of such a wrapping machine is an irregular one, due in part to the fact that the usual cross section of the coil is not circular, and ordinarily it has been considered desirable to center the portion of the coil being wrapped relatively to the shuttle. Relative adjustment between the coil and the shuttle is effected in the machine illustrated by mounting the supporting rolls 8 of the shuttle on a frame 20 pivoted at 22 at the center of the driving disc 10 so that the entire frame may be swung bodily to raise and lower the center point of the shuttle in an approximately vertical direction, the frame being secured in adjusted position by means of the clamping bolt 24 working in an arcuate slot 26 in the frame 20.

The range of work which may be handled by a machine constructed as just described is a somewhat limited one. Usually the strip is packaged in the form of a roll R and is mounted on a spindle placed substantially half-way between the inner and outer diameters of the shuttle, that is, substantially on the mean circumference. The roll R ordinarily would be of a diameter greater than the face width of the shuttle when new to permit as large a supply as possible to be dispensed without the necessity of changing the rolls, but in the drawings the roll R is shown as of very small diameter so as not to obscure other parts of the mechanism and represents the condition where a considerable portion of the supply of wrapping strip has been used. The opening in the center of the coil C or like article must at any rate be such as to pass the shuttle and in the case of a coil of small diameter the roll must not strike the inner surface of the lower portion of the coil and in the case of a coil of large diameter it must not strike the outer surface of the upper portion. The cross section of the coil being wrapped is also a factor to be considered. While coils of a section just small enough to pass the gap 28 of the shuttle could be introduced in the machine, they could not heretofore ordinarily be wrapped because they would interfere with the supply roll for the strip.

I herein provide greater utility for such a machine as has been described by providing a co-operating adjustment of the roll itself in connection with means permitting the control of the supply independently for all relative positions of roll and coil, all of which may be termed a tension mechanism and which may be, as herein shown, organized as a unit on a plate or base 30

(see Fig. 2) adapted to be secured to the shuttle of any machine of this general type. From one point of view the plate 39 might be considered as functionally a part of the face of the shuttle.

The roll R of wrapping material, which, as already explained, is shown small in the figures so that it will not obscure other parts of the mechanism, is mounted on a spindle 32 projecting from a plate 34 secured to the base plate 30 by a pivot bolt 36 and a clamping bolt 38 received in an arcuate slot 40 which permits the plate 34 to be swung about the pivot and clamped in desired position so that the center of the roll may be positioned to move in a path substantially different from the mean circumference of the shuttle. Such bodily movement of the roll-supporting means is facilitated by the fact that I do not attempt to control the movement of the roll as usual by control of the spindle on which it is mounted, and hence the spindle 32 may be a mere pin about which the roll turns to pay out the strip irrespective of the position of the roll relative to the center of the shuttle. Also the roll need not have any core, the omission of which is the most desirable economy.

The strip S is here shown as leading from the roll through a tension device embodying a pair of bars 42 about which the strip may be selectively threaded and through an edge folding mechanism 44, here illustrated as of the type shown in the patent to Wheildon 1,692,236, and leaves the shuttle over a terminal guide roller 46 and passes inwardly to the article being wrapped. To control the roll R on the spindle 32 and also to hold it in position thereon I provide an arm 48 pivoted on a stud 50 and having a broad face engaging the side of the roll, as best seen in Fig. 3, the arm being pressed against the same by spring 52. The outer side of this arm is provided with a flange 54 which overlies the outer base of the roll and holds it in position on the overhanging spindle 32. The arm is herein shown as provided also with an extending lug 56 forming a handle. To load the machine the handle 56 may be grasped and the arm 48 swung counterclockwise, viewing Fig. 2. The roll, which, as has been explained, preferably has no core but is a mere strip of paper coiled up on itself with a central opening or eye of approximately the diameter of the spindle 32, is placed over the latter by a mere movement of approach, and when the arm 48 is released, the flange 54 will overlie the base of the roll and retain it in position while the arm presses against the periphery of the roll and prevents it from spinning.

I have here shown as pivoted on the same center as the guide roller 46 an arm 58 having attached thereto a spring 60 which normally tends to swing it counterclockwise against stop 62, as shown in Fig. 2. Projecting from the end of this arm is a roller 64 adapted to engage laterally the strip as it extends between the guide roller 46 and the coil and to be displaced thereby against the action of the spring 60, as illustrated in Fig. 1. This roller thus constitutes a dance roll, and if, for example, on account of the non-circular cross section of the article being wrapped there is a sudden change in the speed of drawing off the wrapping strip tending to slacken the same, the slack is released to the action of the spring 60 which takes it up.

In the case of a coil of large cross section the plate 34 with the roll thereon may be adjusted outwardly to the position shown in the drawings,

bringing the roll, even when of much larger size than illustrated, into a path which will clear the exterior surface of the coil. In the case of a very small coil the upper portion thereof may be positioned relatively low in the shuttle below the center thereof. Adjustment of the roll in this instance may be such that it will just clear the inner periphery of the lower portion of the coil. While the roll is then moving eccentrically about the part of the article being wrapped, I have found that the control shown permits the dance roll 64 to control the movement of the strip so that an even application thereof to the article being wrapped is effected.

I am aware that the invention may be embodied in other specific forms without departing from the spirit or essential attributes thereof, and I therefore desire the present embodiment to be considered in all respects as illustrative and not restrictive; reference being had to the appended claims rather than to the foregoing description to indicate the scope of the invention.

I claim:

1. Strip dispensing mechanism for the revolving shuttle of a coil wrapping machine embodying means for supporting and rotating the coil through the eye of the shuttle and means for supporting and revolving the shuttle providing for moving the same bodily with reference to the coil comprising a member having means for attaching it to the face of the shuttle and having projecting in overhanging relation from the face thereof a spindle for receiving a roll of wrapping strip, said attaching means providing for adjustment of the member in the plane of revolution of the shuttle to permit substantial differentiation between the path of a roll on said spindle and the path of the shuttle.

2. Strip dispensing mechanism for the revolving shuttle of a coil wrapping machine embodying means for supporting and rotating the coil through the eye of the shuttle and means for supporting and revolving the shuttle providing for moving the same bodily with reference to the coil comprising a member having means for attaching it to the face of the shuttle and having projecting in overhanging relation from the face thereof a spindle for receiving a roll of wrapping strip, said attaching means providing for adjustment of the member in the plane of revolution of the shuttle to permit substantial differentiation between the path of a roll on said spindle and the path of the shuttle, and a dance roll engaging the strip as it leads from said member to the coil being wrapped so that the strip passes immediately from said dance roll to the coil for cooperation with the strip as it passes to the article being wrapped.

3. Strip dispensing mechanism for the revolving shuttle of a coil wrapping machine permitting utilization of a coreless roll of strip comprising a spindle having a free end over which the roll may be placed to turn thereon, a spring-pressed arm opposing the side of a roll so placed and having a flange to overlie the base of the roll, mechanism at the outgoing side through which the strip may lead adapted to place a substantial restraint on the unwinding thereof, and a dance roll positioned to engage the bight of the strip between said mechanism and the coil being wrapped.

4. In a machine for wrapping a coil or the like helically with strip comprising a revolving shuttle and means for supporting and rotating a coil through the eye of the shuttle, the machine hav-

ing provision for adjusting the relative spacing of the centers of the shuttle and coil, a device mounted on the shuttle for supporting a supply of wrapping strip to pay out therefrom in all positions of said device, the mounting providing for the selective positioning thereof throughout a wide range of positions at different distances from the center of the shuttle.

5. In a machine for wrapping a coil or the like helically with strip comprising a revolving shuttle and means for supporting and rotating a coil through the eye of the shuttle, the machine having provision for adjusting the relative spacing of the centers of the shuttle and coil, a device mounted on the shuttle for supporting a supply of wrapping strip to pay out therefrom in all positions of said device, the mounting providing for the selective positioning thereof throughout a wide range of positions at different distances from the center of the shuttle, a guide on the shuttle over which the strip may be led from

the shuttle to the coil, and a spring-pressed swinging arm on the shuttle having a roll laterally to engage the strip so led between the shuttle and the coil.

5. 6. In a machine for wrapping a coil or the like helically with strip comprising a revolving shuttle and means for supporting and rotating a coil through the eye of the shuttle, a spindle projecting from the face of the shuttle having a free end over which a supply of wrapping strip in the form of an open-centered roll may be freely placed, an arm having a wide end portion opposing the side of a roll so placed and a flange to overlie the outer base of the roll, a spring tending to move the arm toward the spindle, a roller about which the strip leads from the shuttle to the coil, and a swinging spring-pressed arm having a roller carried thereby for laterally engaging the strip between the first mentioned 20 roller and the coil.

HARRY W. BROWN.

CERTIFICATE OF CORRECTION.

Patent No. 2,254,934.

September 2, 1941.

HARRY W. BROWN.

It is hereby certified that error appears in the printed specification of the above numbered patent requiring correction as follows: Page 2, second column, lines 56, 57, and 58, strike out the words "for cooperation with the strip as it passes to the article being wrapped"; and that the said Letters Patent should be read with this correction therein that the same may conform to the record of the case in the Patent Office.

Signed and sealed this 28th day of October, A. D. 1941.

Henry Van Arsdale,
